(57) **CLAIM**

The ornamental design for a flying insect trap, as shown and described.

DESCRIPTION

FIG. 1 is a front view of the trap.

FIG. 2 is a rear view thereof.

FIG. 3 is a first side view thereof.

FIG. 4 is a second side view thereof.

FIG. 5 is a top view thereof.

FIG. 6 is a bottom view thereof; and,

FIG. 7 is a perspective view thereof.

The broken line showing of environment in the drawings is included for the purpose of illustrating only and forms no part of the claimed design.

1 Claim, 4 Drawing Sheets
